UNITED STATES PATENT OFFICE.

LEONIDAS W. LOVELESS, OF LAFAYETTE, INDIANA.

CASH-BOX.

SPECIFICATION forming part of Letters Patent No. 319,498, dated June 9, 1885.

Application filed May 10, 1884. (No model.)

To all whom it may concern:

Be it known that I, LEONIDAS W. LOVELESS, of the city of Lafayette, county of Tippecanoe, and State of Indiana, have invented 5 certain new and useful Improvements in Cash-Boxes, of which the following is a specification.

The object of my said invention is to provide a convenient and safe cash-box into which 10 specie may be dropped as it is received and taken out as it is needed, all without the usual trouble of opening the box or pulling out a money-drawer. This object is accomplished by providing a series of tubes of several sizes 15 to accommodate the various denominations of coin, forming slots in the cover thereto, through which the coins may be dropped into said tubes, forming an opening in the front side of each tube at its bottom large enough for one 20 coin to pass through, and providing push-bars, which are operated back and forth in the bottom by means of bell-crank levers or like devices operated by push-pins in the top of the box, and thus push a coin through said opening at every operation of said push-bars, as will 25 be hereinafter more particularly described.

Referring to the accompanying drawings, which are made a part hereof, and on which similar letters of reference indicate similar 30 parts, Figure 1 is a top or plan view of my improved money-box, a portion being broken away to show the interior; Fig. 2, a front elevation of the same, the casing being broken away to show the interior; Fig. 3, a rear elevation, the casing being also broken away to give a rear view of the interior; Fig. 4, a trans- 35 verse vertical section on the dotted line $z z$ through the locking device, the whole lines representing the locked position and the dotted lines the unlocked; and Fig. 5, a trans- 40 verse vertical section on the dotted line $y y$, showing one of the tubes, push-bars, and most of the operating mechanism in central section.

In said drawings, the portions marked A re- 45 present the casing of the box; B, a drawer for currency; C, the tubes for specie; D, sliding push-bars; E, the bell-crank levers for operating said push-bars, and F a locking device which operates both to lock the drawer and 50 close the tubes.

The case A may be formed of wood or cast from metal, or otherwise, as desired. It is of

the appropriate size to incase the tubes, drawer, and mechanism connected with the box. It has a partition, A', between the tubes and drawer, which serves as the top to the drawer and the base on which the sliding push-bars and other mechanism are mounted. The front part of the top is hinged, and forms a lid or cover, A², for the tubes. It is provided with 55 slots a , through which the coins are dropped into the tubes, there being one provided for each tube. At the rear of this hinged part a row of holes is provided, in which the push-pins for operating the mechanism are mounted, 60 as shown.

The drawer B is mounted in the lower part of the case on suitable cleats or slides, as usual, and is of any desired construction, it being designed for the accommodation of bills, 7c checks, &c. If it is desired to have only a specie-box, the drawer can be omitted, as the operation of the other parts depends in no manner upon said drawer. Notches b are formed in the front top corners of the drawer, 75 with which the locking device F engages, as will be presently described.

The several tubes C are preferably cast together, webs c being formed between them. They are secured in position in front of the 80 box on the partition A' in any desired manner. At the lower end of each tube the front and rear sides are cut away sufficiently to allow a coin to be pushed out through the front and the push-bar to enter through the rear 85 side. The lower ends of these tubes are each formed of substantially the same size as the coin which it is intended to accommodate, and are flared slightly toward their tops, as shown. The top face of said partition A' forms the 90 bottom of said tubes, and is preferably cut away on its front side, where the tubes rest, about the thickness of a coin, so that said coin will drop directly in front of the push-bar, which slides in the top of said partition, as 95 will be presently described. They are of the height to make them of the capacity desired. There may be as many of the tubes as there are different denominations of coin in use. In the drawings nine are shown, this being the 100 number of denominations of coin in most general circulation—viz., one cent, five cents, ten cents, twenty-five cents, fifty cents, one dollar, five dollars, (gold,) ten dollars, (gold,) and

twenty dollars, (gold;) but, as will be readily understood, as many more may be added as seems necessary, or, for some uses, some of those shown may be left out, the discharging mechanism for each tube acting entirely independently of that for each of the several other tubes.

The sliding push-bars D are mounted in slides in the top of the partition A' behind the tubes C, there being a push-bar for each tube. They are provided on their top side with studs d, or similar means of connection to the bell-crank levers by which they are operated. These studs d are preferably formed as shown, each being flat in its middle portion, with which the corresponding bell-crank lever engages, as will be presently described. They are provided with flanges d' on each side, which prevent the levers from slipping off said studs. Said push-bars are of sufficient length, so that when pushed forward they will extend through under the tubes and push out the lower coin. Their front ends are preferably formed with a circular notch therein, which fits against the coin upon which they operate.

The bell-crank levers E are pivoted on a rod, e, which extends longitudinally through the box, having its bearings in the ends of the casing. The lower end of the vertical arm of each of the levers is preferably bifurcated, as shown, and straddles the central portion of the stud d on the corresponding push-bar. The top or horizontal arms of the levers extend back, and are connected to the push-pins E', by which they are operated. The levers, and through them the push-bars, are drawn back by means of the coiled springs e', which are connected to the vertical arm of the levers just above their connection with the push-bars, and to a staple or stud in the top of the bar A', which is secured in the rear part of the box by screws inserted through the case into its ends, or in any other suitable manner.

The push-pins E' are formed to slide vertically in bearings provided in the top of the casing, as shown. They are of sufficient length to give the levers the required stroke, being pivoted to said levers at their lower ends. The top of each pin may be marked, as shown in the drawings, or preferably has a representation of the coin which the corresponding tube is designed to contain, and thus the user is enabled to see at a glance which pin to push down upon to throw out the desired coin, as will be presently more fully described.

The locking device F consists of a bar extending across in front of the lower ends of the tubes, just above their outlets, which is provided with an upright, f, at each end, which extends up through the guides f' to the top of the box. These uprights also extend down through holes in the partition A', and are adapted to engage with the notches b in the corners of the drawer B. On the rear side are lugs f'', with which springs F' will engage, said springs being secured on the partition A' at the rear side of the uprights, and said

locking device is thus held up in an unlocked position when in its normal position. It is operated as follows: Lugs a'' are provided on the under side of the lid A'', which are adapted to come in contact with the top ends of the uprights f when the lid is shut down, and thus bear them down into the notches in the top of the drawer, and at the same time the bar is borne down in front of the outlet to the tubes. The lid then being locked, the several parts are thus all securely fastened at one operation.

The operation of my said invention is as follows: The cashier or other person receiving the money drops the coins as received into the appropriate tube through the slots in the lid A''. The tube being of but little larger size than the coin, it keeps them in a straight pile directly on top of each other, the bottom one always being directly in front of the push-bar. When it is desired to take out a coin to make change, or for any other purpose, the proper push-pin is pushed down, which, through the bell-crank lever E, pushes forward the push-bar, which pushes out the coin in the bottom of the tube through the opening a' in the front of the box, where the operator catches it. Each of the several push-pins operates in the same manner to throw out the bottom coin in its tube when pushed down. The spring at the rear of the bell-crank lever immediately pulls the push-bar and other mechanism back into place as soon as the pressure upon the push-pin is removed, when the next coin comes into a position to be thrown out by the next operation of said mechanism. When two or more coins are wanted out of any one tube, the mechanism is operated as many times as there are coins desired.

The drawer B is for bills, checks, &c., and is used in the ordinary manner.

When it is desired to lock the box, the lid A'' is simply pushed down closely and locked, which operation locks the drawer and closes the outlet from the tubes, as before described. The lock of the lid being preferably a spring-lock, it is only necessary to push said lid down closely upon the case, when the whole device is immediately securely fastened up.

Having thus fully described my said invention, what I claim as new, and desire to secure by Letters Patent, is—

1. In a cash-box, the combination of the case A, having a horizontal partition, A', a series of tubes mounted on said partition, push-bars, also mounted on said partition behind said tubes and adapted to be slid into the lower end thereof, said push-bars being provided with studs on their top surface, bell-crank levers pivoted on suitable bearings, the end of one arm of which levers is bifurcated and connected with the studs on the top of the push-bars, the end of the other arm being connected to a push-pin which operates in the top of the case, and said push-pin, substantially as set forth.

2. In a money-box, the combination of the case A, having a partition, A', the drawer B,

mounted in said case under the partition, tubes C, mounted on the front edge of said partition, with openings in the lower front corners for the discharge of the coins, and the locking device F, consisting of a bar extending across 5 in front of the tubes and having an upright, f, mounted on each end thereof, the lower ends of which extend below the bar sufficiently to enter notches in the upper corners of the 10 drawer, and the upper ends of which extend up sufficiently to engage with the lid A² of the case, whereby the closing and locking of said lid operates to press said uprights down into the notches in the drawer and the bar down 15 in front of the openings in the tubes, and thus lock all the outlets of the box at one operation, substantially as set forth.

3. In a cash-box, the combination of the case A, having a partition or floor, A', drawer 20 B, mounted therein, the tubes C, also mounted in the case on the floor A', push-bars D, mounted in slides in said floor A', and provided with studs d, bell-crank levers E, pivoted on a shaft, e, one end being connected to said 25 stud d and the other end to a push-pin, E', and said push-pin E', mounted in the top of the case, substantially as described, and for the purposes specified.

4. The combination, in a cash-box, of 30 the case A, having a partition or floor, A', drawer B, mounted in said case below said floor, tubes C, mounted on the front edge of said floor, lid A² to said tubes, hinged to the top of the case, push-bars D, bell-crank levers 35 E, push-pins E', and locking device F, said locking device having uprights f, which extend up to the lid, and said lid being adapted to come in contact with the tops of said up-

rights and bear them down into notches in the top of said drawer as said lid is closed and 40 the bar down in front of the outlets to the tubes, all substantially as described, and for the purposes specified.

5. In a cash-box, the combination of the case A, partition or floor A', tubes C, mounted 45 on said floor, push-bars D, having studs d and mounted in slides in said floor, shaft e, extending through said box and having bell-crank levers E mounted thereon, said bell-crank levers, the vertical arms of which are connected 50 to the stud d on the push-bars D, springs connected to said bell-crank lever, and the push-pins E', extending down through the top of the box and pivoted to the top arm of the bell-crank lever E, substantially as set forth. 55

6. In a cash-box, the combination, with the drawer B and tubes C, provided with a lid, A², of the locking device F, consisting of a bar mounted in front of the tubes and having uprights f on each end, mounted in guides 60 f', and having lugs f² upon their rear sides, which engage with springs F', said springs F', and the lid A², said lid being adapted to engage with the top ends of said uprights f, whereby said uprights and the bar are borne 65 down as the lid is closed, and thus the locking of said lid operates to lock said drawer and close said tubes, substantially as set forth.

In witness whereof I have hereunto set my hand and seal, at Lafayette, Indiana, this 6th 70 day of May, A. D. 1884.

LEONIDAS W. LOVELESS. [L. S.]

In presence of—

LÆW DODD,
GEORGE DUNKERLY.
